Primary Examiner — Michelle E. Wilson

Assistant Examiner — Clese Moore, Jr.

(57) **CLAIM**

The ornamental design for a square-necked long-sleeved shirt, as shown and described.

DESCRIPTION

FIG. 1 is a perspective view of a square-necked long-sleeved shirt showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view thereof, showing the square-necked long-sleeved shirt in a state of use.

The broken lines in the drawings depict portions of the square-necked long-sleeved shirt that form no part of the claimed design.

1 Claim, 8 Drawing Sheets
